UNITED STATES PATENT OFFICE.

PAUL GROSSER, OF ALBERSDORF, GERMANY.

HYDROPLANE AND AEROPLANE.

1,136,420.

Specification of Letters Patent. Patented Apr. 20, 1915.

Application filed March 28, 1913. Serial No. 757,440.

To all whom it may concern:

Be it known that I, PAUL GROSSER, a citizen of the German Empire, and residing at Albersdorf, Holstein, Germany, have invented certain new and useful Improvements in Hydroplanes and Aeroplanes, of which the following is a specification.

The subject-matter of my invention is an improved hydroplane which is also arranged for landing and starting on *terra firma*. For this purpose the flying machine is provided with floats and also with wheels for starting which can be drawn upward. The floats are provided with gliding planes in order to lift the machine out of the water when traveling thereon.

The invention consists in the construction, arrangement and combination of parts described hereinafter and pointed out in the claims.

One illustrative embodiment of my invention is represented by way of example in the accompanying drawing, wherein:—

Figure 1 is a side elevation showing a flying machine according to my invention, but without carrying planes; Fig. 2 is a plan view showing a float with a wheel for starting; Fig. 3 is a detail view showing the apparatus for winding up the wheels for starting for traveling on water, and Fig. 4 is a section through the cock for the device for emptying the float.

Referring to the drawing, the body or frame *a* of the flying machine rests on one or two front floats *b* and a rear float *b'*. The front float or floats is or are located approximately under the center of gravity of the flying machine, while the rear float is arranged under the vertical rudder *s* and is connected with the axis *t* of the latter. When the machine is on the water the front floats carry the greater part of the weight, while the rear float enables the machine to be steered and aids in preventing the machine tilting. Each front float carries a gliding plane *c* adjustably mounted in a slanting position. Two wheels *d* for starting are located one at each side of the one or two front floats approximately under the center of gravity in the manner which will be readily understood from Figs. 1 and 2,

each wheel *d* being carried by a fork *e* able to rock about an axis *e'* carried by the one or more front floats. The fork *e* of each wheel is connected with the frame *a* of the machine by an elastic connection *f* which may be, for example, a rubber tie or a tensile spring. Owing to the tension of this spring *f* the wheels are pressed downward. In order that the wheels may offer no resistance in the water when the machine is traveling on the water they can be wound upward by the crank-handle *k* of the winch *i* by means of the ropes *h*, the handle *k* or the winch being fixed in its position for the time being by a pawl, brake or other arresting device. When this arresting device is released the wheels *d* are pressed downward by the tension of the springs *f* or the like, so that the machine can land on the wheels *d*, the springs *f* taking up the blow due to landing. Instead of tensile springs *f* being used, compressed springs or other elastic members which take up pressure may be used; they must, however, act on the other side of the fork *e* or the axle of the wheels *d*, as is represented by the compressed springs provided in tubes *g* shown in Fig. 1.

I claim:—

1. In a hydroplane, the combination with the frame, a rear float and a front float carried thereby, of an axis carried on the front float, forks, each carrying a wheel, mounted to rock about the axis, springs tending to rock the forks and drive the wheels downward, and a winch mounted on the frame and operatively connected with said forks for rocking the same against the action of said springs and thereby elevating the wheels.

2. In a hydroplane, the combination with the frame, a rear float and two front floats carried thereby, of an axis carried by the front floats, two forks, each carrying a wheel, mounted to rock about said axis and located outside the front floats, an upwardly slanting plane adjustably mounted on each front float and embracing parts of the sides and the front end thereof, springs tending to rock the forks and drive the wheels downward, and a winch mounted on the frame and operatively connected with said

forks for rocking the same against the action of said springs and thereby elevating the wheels.

3. In a hydroplane, the combination with the frame, and front and rear floats carried thereby, of an angularly adjustable plane mounted on each front float, each plane extending laterally on both sides of the front

portion of the float on which it is mounted.

In testimony whereof, I affix my signature in the presence of two witnesses.

PAUL GROSSER.
